INVENTOR,
Chas. F. Miller
BY Green & McCallister
ATTORNEYS.

UNITED STATES PATENT OFFICE.

CHARLES F. MILLER, OF MORTON, PENNSYLVANIA, ASSIGNOR TO WESTINGHOUSE ELECTRIC & MANUFACTURING CO., A CORPORATION OF PENNSYLVANIA.

STOKER.

1,406,884.

Specification of Letters Patent. Patented Feb. 14, 1922.

Application filed August 31, 1917. Serial No. 189,200.

To all whom it may concern:

Be it known that I, CHARLES F. MILLER, a citizen of the United States, and a resident of Morton, in the county of Delaware and

5 State of Pennsylvania, have made a new and useful Invention in Stokers, of which the following is a specification.

This invention relates to mechanical stokers and more particularly to stokers operating on the underfeed principle.

Underfeed stokers are usually provided with at least one retort into which green or fresh fuel is fed at a point below the air supplying

10 passages to the furnace, so that the fuel entering the furnace is subjected to the heat of combustion before it enters the combustion zone and before it is supplied with adequate air to support free combustion. By introducing the fuel into the furnace in this way

15 some of the volatile constituents are distilled off and the fuel is partially or wholly converted into coke before reaching the combustion zone, where sufficient air is delivered to the fuel to support free combustion. It is,

20 of course, understood that the volatile constituents distilled from the incoming fuel are not lost, but are mixed with sufficient air to promote complete combustion as they pass through the combustion chamber of the

25 furnace. In order to obtain complete combustion of the coked or partially coked fuel it is customary to cause it to pass over an overfeed section before it is discharged from the furnace into the ash pit. For the purpose of this specification, the term "overfeed section" may be defined as a fuel supporting member across which fuel is fed and to which air is so delivered that it enters the furnace below the fuel supported on the

30 member.

An object of my present invention is to produce a new and improved mechanical stoker of the combined underfeed and overfeed type.

35 A further object is to produce an underfeed stoker in which new and improved means are employed for completing the combustion of the fuel leaving the underfeed portion of the stoker.

40 A further object is to produce a mechanical stoker to which fuel is fed at a point below the air supply to the combustion chamber and in which new and improved

means are employed for distributing the fuel over the fuel supporting elements as it moves toward the discharge end of the stoker.

45 A further object is to produce a stoker in which improved means are employed for mounting fuel supporting members and for delivering the consumed fuel on to the dump grate mechanism.

50 A further object is to produce an improved power actuated dump grate mechanism.

55 A further object is to produce an underfeed stoker in which improved means are employed for aiding the delivery of fuel into the retort.

60 These and other objects are attained by means of apparatus embodying the features herein described and illustrated in the drawings accompanying and forming a part hereof.

65 In the drawings: Fig. 1 is a transverse sectional view of a stoker embodying my invention.

70 Fig. 2 is a fragmental transverse sectional view of the stoker illustrated in Fig. 1, the view being on an enlarged scale and illustrating a portion of the dump grate actuating mechanism of the stoker.

75 Fig. 3 is a sectional view along the line 3-3 of Fig. 2.

80 Fig. 4 is a fragmental perspective view showing the forward ends of overfeed grate bars and illustrating the arrangement of a fuel breaker which is operatively connected to the moving grate bars and is located within the retort.

85 Fig. 5 is a fragmental perspective view illustrating the rear ends of several grate bars and the means employed for mounting them on the stoker frame.

90 In a copending application entitled "Underfeed stokers," filed May 21, 1917, and serially numbered 169,932, I have illustrated and described a stoker which is similar to the stoker herein illustrated in that it includes an underfeed section comprising a retort 10, which extends across the front of the furnace and to which fuel is fed, at

95 points below the air or blast admission passages, by means of fuel feeding plungers 11. The plungers are located at the front of the furnace and are actuated by a fuel feeding

mechanism also located at the front of the furnace. The fuel after entering the retort 10 is delivered on to and across an overfeed section, illustrated as including a series of 5 alternately arranged reciprocating and stationary grate bars 12 and 12' which extend from the retort 10 rearwardly toward the dump grate mechanism 13 of the furnace.

10 In the present application and in the previous application, above mentioned, the retort 10 is formed by the cooperation of so-called retort bodies 15, an inclined table 16 and the forward ends of the stationary and 15 reciprocating grate bars 12 and 12'. The bodies 15 form a portion of the front wall of the furnace and each body is relatively narrow and is mounted on the inclined table 16, which forms the floor of the retort 10. Each 20 body 15 includes a fuel hopper 17 located at the front of the furnace, and a fuel delivery passage which establishes communication between the lower end of the hopper and the retort 10 and forms a guide in which one of 25 the plungers 11 operates. Each body also includes an air box 18, the rear and air delivery wall of which forms the front wall of the retort 10. The inclined table 16 may also be formed in short sections for convenience 30 of manufacture and assembling, and its forward edge is shown mounted on a box section 19, which preferably extends the width of the furnace and forms the lower wall of the stoker. The rear edge of the inclined table 35 is mounted on a support bar 20, which extends across the furnace and is mounted at intermediate points on pedestals 21. The pedestals are suitably mounted on frame members 22, which are supported by suitably 40 spaced beams 22^a forming the foundation frame of the stoker. The grate bars 12 and 12' are shown inclined downwardly from the retort 10 toward the rear of the furnace. Each bar is mounted at its upper and forward 45 ends on a support plate 21^a, which extends from one side wall to the other of the furnace and which is supported at intermediate points on the pedestals 21. The lower ends of the grate bars are mounted on 50 an element 32 which forms a part of the air box 24.

Partition plates 26 are mounted on the frame members 22 and divide the space below the fuel supporting members into two 55 chambers 25 and 25^a; the former of which may be termed the primary air chamber, since it receives air under pressure through conduit 27 and delivers it to the air box 24 from which it is delivered to passages in the 60 bars, forming blast distribution passages. The chamber 25^a may be termed the secondary air chamber, since it receives air after it has traversed passages within the grate bars and consequently after it has taken up 65 heat in the operation of cooling the bars.

Air from this chamber is delivered to the fuel bed through spaces located between the grate bars. Air from the chamber 25^a is also delivered to the air box 18, as described in my previous application.

One feature of my present invention is the new and improved means for mounting the lower ends of the grate bars. As illustrated, 70 a bracket 30 is mounted on a channel 31 which forms the rear member of the stoker frame and which in turn is supported on a beam 22^a. The bracket 30 performs a three-fold function; that of supporting the dump grate mechanism; of partially enclosing the air box 24; and of supporting the lower ends 75 of the grate bars 12 and 12'. The grate bars, however, are not directly mounted on a bracket 31, but are mounted on the member 32, which is pivotally mounted on the bracket. The member 32 is preferably 80 formed in short sections, (see Figure 5), which are so arranged as to form the rear wall of the air box 24. As illustrated, each section of the member 32 consists of a web 85 having cylindrical top and bottom flanges. The lower flange is mounted in a suitable bearing, provided on the bracket 30 and is so arranged that the member is capable of 90 rocking in its bearings in response to the reciprocating motion of the grate bars. The lower end of each moving grate bar is provided with downwardly projecting lugs 32^a and 32^b adapted to engage the upper flange of the member 32 and each bar is preferably 95 so supported by the member that it moves free of the front wall of the air box. With this arrangement the moving bars impart motion to the sectional member 32. The stationary grate bars are provided with lugs 100 12^a and 12^b, which respectively engage the plate 21^a and the forward wall of the air box 105 24 and prevent the bearing from moving. The rear end of each stationary grate bar may be wholly or partially supported on the moving member 32 and, as illustrated, is 110 provided with downwardly projecting lugs similar to the lugs 32^a and 32^b of the moving bars, but which are spaced sufficiently far apart to permit the member 32 to move in both directions throughout its entire 115 travel, without tending to impart motion to the stationary bars.

Reciprocatory motion is imparted to the moving grate bars by means of a rocker bar 34 which is similar to the rocker bar in the 120 application to which I have referred.

For the purpose of breaking up the fuel as it enters the retort, I have provided an apron 35, which is secured to the forward ends of the moving grate bars and which overlies a 125 portion of the inclined table 16. This apron is preferably formed in short sections, each section somewhat less in width than the width of the retort body. As illustrated, each section is secured to one moving grate bar by 130

means of a hinge connection, which permits the forward edge of the apron to move across the surface of the table and at the same time causes the apron to move with the grate bars.

5 Another feature of the invention is the dump grate mechanism and the operating apparatus forming a part of that mechanism. As illustrated, the stoker is provided with a single leaf dump grate 36 which is preferably, though not necessarily, formed in section corresponding in width to the width of the retort bodies 15. The sections are mounted on a shaft 37, which is journaled at the rear of the stoker frame, as for example, 10 on the bracket 30. The free end of the grate 36 extends in close proximity to the bridge wall 38 and, as illustrated, is actuated from the front of the furnace by the apparatus employed for imparting motion to the grate 15 bars and for actuating the plungers 11.

As illustrated in the present application and as described and illustrated in the application to which I have referred, the stoker is provided with an operating shaft 38, 20 which is suitably mounted at the front of the stoker and which actuates the plungers 11 through the agency of gear and rack connections. Power is also delivered to the moving grate bars from the shaft 38 by means 25 of a lever arm which engages and is adapted to impart reciprocatory motion to a rod extending through the front wall of the stoker. This rod in turn imparts motion to the rocker bar 34.

30 As illustrated, the actuating mechanism of the dump grate 36 includes a lever or arm 39 rigidly mounted on the shaft 38, an adjustable connection 40, pivotally connected to the arm 39 and also to a bell crank lever 41. The lever 41 imparts motion to a link 42, which in turn, actuates a rod 43. The link imparts reciprocatory motion to the rod, which motion is imparted to the grate 36 through the agency of a rack 44 mounted on 45 the rod, a gear 45 meshing with the rack, and a link 46 operatively connected to the gear, or to the shaft on which the gear is mounted, and also operatively connected to the grate bar 36. In the apparatus illustrated, the shaft 38 is periodically turned back and forth by means of a motor 47, and a connecting rod 48 actuated by the motor, and pivotally connected to an arm 49, rigidly mounted on the shaft 38. With 50 such an arrangement the amplitude of the arm 39 is constant and consequently the apparatus actuated by the arm 39 would operate to fully open and again close the dump grate 36 each time the shaft 38 completed 55 a cycle of operation. In order that the operation of the dump grate mechanism may be independently controlled and also that the grate may be moved to any desired dumping position, I have provided manually adjustable means, which in effect operates

periodically to break the operative connection between the dump grate mechanism and the actuating arm 39, or which may be so adjusted that the arm 39 may oscillate without actuating the dump grate mechanism. 70

As illustrated, this is accomplished by means of the member 40, the operation of which is controlled by a sleeve 51, which surrounds a portion of the member 40 and is capable of being moved to different positions by means of a worm 52, a segmental gear 53, an arm 54, a link 55, and a pivoted frame 56, to which the sleeve 51 is secured by means of a pivotal link 57. The frame 56 is pivotally mounted on a bracket 56^a 80 secured to the front of the stoker and the operating shaft 58 of the worm 52 is journaled in this bracket and is provided with a hand wheel 59, which is so located as to be convenient to the stoker operator. The 85 gear 53 is suitably mounted on a pin 60, which is shown mounted on the bracket 56^a. In Figure 3 of the drawings the arm 54 is shown split or formed in two parts, both of which are integrally formed with hub 90 portion of the gear 53. The frame 56 is shown bifurcated at its free end and two links 57 are employed between it and the sleeve 51.

As illustrated the member 40 includes a 95 rod 61, which is pivotally secured to the arm 39 and projects downwardly into a tubular casing 62 provided at its lower end with a pair of dogs 63. These dogs are normally pressed inwardly or toward each other 100 by means of a spring 64 and are adapted to engage notches formed in the lower end of the rod 61 and to thereby lock the rod and the tubular casing 62 together. The tubular casing carries two trunnions 62^a 105 which form an operative connection between the member 40 and the bell crank 41. The bell crank 41 is shown in the drawings as a double bell crank, the separate parts being mounted on the pin 60 on opposite 110 sides of the gear 53 so that each engages one of the oppositely located trunnions 62^a of the casing 62.

As is apparent from the drawing, the arm 39 imparts reciprocatory motion to the tubular casing 62 when the dogs 63 are in engagement with the rod 61. The normal dumping operation is as follows: The hand wheel 59 is turned so as to raise the frame 56 and consequently the sleeve 51 to such position 120 that it will not be engaged by the dogs 63 as they move in response to the motion imparted to the casing 62 by the rod 61. Under such conditions the dump grate 36 will be moved from the normal position indicated 125 in full lines in Fig. 1 to the upper position indicated in dot-dash lines in Fig. 1. From this upper position it will move downwardly to the wide open or full dumping position. This entire motion of the dump grate takes 130

place during the upward movement of the arm 39 or as the rack 44 is moved outwardly and the gear 45 is moved in a counter clockwise direction. The positioning of the arm 45^a with relation to the final position of the gear 45 and also with relation to the link 46, causes the dump 36 to first move upwardly before it starts to move downwardly to dump the refuse and ash contained on it. This upward swing is of material advantage, since it breaks clinkers free from the bridge wall and aids the dumping operation. As the arm 39 moves downwardly the gear 45 moves back and in a clockwise direction. This 10 swings the grate 36 upwardly to the dot-dash position indicated above to the full line position of the grate and finally causes the grate to move downwardly to the normal position. The amount of opening motion imparted to the dump grate mechanism is controlled by the position of the sleeve 51, which operates to engage the dogs 63, as the tubular casing 62 moves upwardly, and to thereby move the dogs outwardly and out of engagement with the rod 61. This breaks the operative connection between the arm 39 and the dump grate mechanism. In order that the dump grate, when so released, will not fall by gravity to the extreme dumping position, I have provided a stop 64^a between the two parts of the bell crank lever 41, which is so positioned that it is adapted to engage the arm 54 at the time the dogs 63 are released by the sleeve 51. With such an arrangement the stop 64^a is held against the arm 54 by the weight of the dump grate and consequently the dogs 63 are held outwardly by means of the sleeve 51 until the rod 61 completes its upward stroke and in returning 30 moves the casing 62 downwardly with it, by reason of the fact that its lower end engages a stop 65, which is provided at the lower end of casing 62 and obstructs the passage through the member 62. As soon as the rod 35 engages the stop, motion is again imparted to the dump grate mechanism and the dump grate consequently starts to move toward the closing position. This motion releases the dogs 63 from the sleeve 51 and consequently 40 causes the dogs to engage the rod 61. When the sleeve 51 is in an intermediate position the dump grate is periodically opened and closed and each opening and closing motion causes it to move upwardly above its normal 45 closed position. The amount of opening movement is determined by the position of the sleeve 51.

When it is desired to retain the grate 36 in the closed position the wheel 59 is turned 50 to move the parts actuated by it to the positions indicated in Fig. 1. With the frame 56 and consequently the sleeve 51 in the positions shown in Fig. 1, the rod 61 moves back and forth within the tubular casing 62 without imparting motion to the casing and con-

sequently without imparting motion to the grate 36, since the sleeve 51 holds the dogs 63 out of engagement with the rod 61. With the parts in this position there is no tendency for the grate 36 to move downwardly to the dumping position since a positive stop may be provided to hold the grate in the normal position. As illustrated, the head 66 on the rod 43 forms a positive stop for the dump grate mechanism by engaging an abutment on the front wall of the furnace and through which the rod 43 projects. Inasmuch as the opening movement of the grate is preceded by the upward swing, the head 66 will hold the grate in the normal position independently of the stop 64^a, and consequently the sleeve 51 may be adjusted for the purpose of causing grate to open without the necessity of manually moving the grate.

Another feature of the invention is the 85 method of delivering air to the dump grate 36. This grate is provided with an interior air passage which extends from the forward to the rear edge of the grate and supplies air to twyers 67 located in the fuel supporting face of the grate. In addition to this, the twyers are so arranged that they direct the air delivered through them across the face and toward the rear of the grate. One or more twyer openings 68 are formed at the 90 edge of the dump grate and are so arranged with relation to the interior air passage that ashes or fine material sifting back through the twyers 67 will be blown out of the air passage through the twyers 68. Air is delivered to the interior passage of the grate through an opening formed in the pivoted end of the grate, which is adapted to register with an air delivery port formed in the bracket 30 when the grate 36 is in the initial 95 position. This port is controlled by means of a damper 69 and the damper is in turn controlled from the front of the furnace by means of a system of links and rods including the rod 70.

The operation of the stoker is as follows: The motor 47 oscillates the shaft 38, which in turn imparts reciprocatory motion to the plungers 11 and the moving grate bars 12. The plungers 11 force fuel into the retort 110 and through the retort onto the moving and stationary grates 12 and 12'. The cooperation of the plungers 11 and the moving grate bars 12 cause the fuel to move uniformly toward the dump grate mechanism. The moving grates also break up the fuel bed and tend to prevent the formation of large clinkers. The rocking motion imparted to the sections 32 by the moving grates tends to prevent arching across the 115 dump grate, inasmuch as it agitates and crushes the refuse contained on the grate 36. In addition to this, the sections 32 are provided with air delivery ports 72, which receive air under pressure from primary air 120

chamber 25 and which, together with the twyers 67, deliver air to the fuel contained on the grate 36 and ensure thorough combustion of the fuel before the ash and clinkers 5 are discharged into the ash pit. The damper 69 makes it possible to blast the fuel contained on the grate 36 immediately prior to the dumping operation. The dump grate may be adjusted so that it will periodically 10 oscillate without opening sufficiently to discharge refuse material into the ash pit, or it may be adjusted so that it will not only break up the clinkers and prevent arching, but will also periodically discharge into the 15 ash pit. In wide furnaces one or more shafts 38 will be employed, and the operating mechanism of the dump grate may be divided so that a half, a fourth, etc. of the dump grate 36 is operated from one shaft 38. 20 While I have described and illustrated but one embodiment of my invention, it will be apparent to those skilled in the art that various changes, modifications, additions and omissions may be made in the apparatus 25 illustrated without departing from the spirit and scope of the invention, as set forth by the appended claims.

What I claim is:

1. In combination in a stoker, a dump 30 grate mechanism comprising a pivoted dump grate, and power actuated means for swinging said dump grate first upwardly above the normal closed position, and for then dropping the grate below the normal closed 35 position during the dumping operation.

2. In combination in a stoker, a pivotally mounted dump grate having its free edge in close proximity to the bridge wall of the stoker, and power actuated means for swinging the free edge of the dump grate first upwardly above the normal closed position and then downwardly below the normal closed 40 position during the dumping operation.

3. In combination in a stoker, a dump 45 grate pivoted so that a major portion of its surface may be moved above or below the normal closed position of the grate, and means for first swinging the major portion of the grate above the normal closed position thereof and then dropping the major portion of the grate below the normal closed 50 position during the dumping operation.

4. In combination in a stoker, a dump 55 grate pivoted adjacent one edge thereof so that substantially its entire surface may be swung above or below the normal closed position of the grate, and means for first swinging the grate above the normal closed position to agitate the fuel there above and 60 then swinging the grate to open position below the normal closed position thereof during the dumping operation.

5. In combination in a stoker, a fuel feeding plunger for forcing fuel into the furnace, movable fuel supporting elements for

moving the fuel toward the rear of the furnace, a pivotally mounted dump grate, power actuated means for actuating said plunger, said members, and said dump grate, means for positively connecting the power 70 actuated means with the dump grate during certain portions of the cycle of movement of the power actuated means, and means for adjusting the period of positive connection of the power means with the dump grate 75 including a stop for the dump grate when the positive connection is released.

6. In combination in a stoker, a fuel feeding plunger, power actuated fuel supporting members, a pivotally mounted dump 80 grate and power actuated means for actuating said plunger and said fuel supporting members, and for swinging said dump grate first upwardly from the normal closed position and then downwardly below the normal 85 closed position during the dumping operation, and adjustable means for controlling the operation of said dump grate.

7. In combination in a stoker, fuel feeding means, fuel supporting elements receiving the fuel delivered by said fuel feeding means, a pivotally mounted dump grate, power actuated means for actuating said fuel feeding means, means actuated by said power actuated means for first swinging said 90 grate upwardly above the normal closed position, and then downwardly below the normal closed position into open dumping position, during the dumping operation, and manually adjustable means for controlling 95 the operation of the said last mentioned means.

8. A refuse discharge mechanism for furnaces comprising a dump grate, a power actuated periodically reciprocating member, 105 a casing surrounding said member, dogs mounted on the casing for engaging the member, means actuated by the casing for actuating said grate, a sleeve movable to different positions along the casing for engaging said dogs and for thereby disconnecting the member from the casing and means for adjusting the position of the sleeve so as to vary the amount of motion transmitted to the said grate by said casing. 110

9. In combination in a furnace, a dump 115 grate mechanism comprising a pivotally mounted grate, a rotatable gear for actuating said grate, a rack for actuating said gear, a casing for actuating said rack, a reciprocating member, means carried by the casing for engaging the member, adjustable means for engaging said casing-carried means and for disconnecting the casing from said member. 120

10. In combination in a stoker, a pivotally mounted dump grate, a rotatable gear, a link between said gear and said grate so located with reference to the gear and the grate that the grate is swung upwardly 125 during the dumping operation. 130

ing the first motion of the gear, a rack for actuating the gear, a uniformly reciprocating member, means for engaging said member and for thereby actuating said rack, and 5 adjustable means for controlling the engagement between the said last motion and means of said member.

11. In an underfeed stoker, a retort to which fuel is fed below the surface of the 10 fuel contained therein, grate bars located in parallel relation and forming the rear wall of said retort, means for reciprocating certain of said grate bars and an apron operatively connected to the movable grate bars 15 for breaking up the fuel entering the retort.

12. In an underfeed furnace, a retort, a plunger for forcing said fuel into said retort, movable grate bars for receiving fuel discharged from said retort and means actuated by said grate bars and located within said retort for preventing packing of the fuel entering the retort.

13. In an underfeed furnace, a retort extending across the front wall of the furnace, 25 grate bars located in parallel relation and extending from said retort rearwardly, means for reciprocating some of said grate bars and means actuated by said moving bars and located within said retort for agitating the fuel entering the retort.

14. In an underfeed furnace, a retort, rearwardly extending longitudinal movable fuel supporting grate bars for receiving fuel from said retort, a reciprocating plunger for 35 forcing the fuel into the retort below the surface of the fuel contained therein and means actuated by said moving grate bars projecting into the retort and adapted to move toward the said plunger for agitating 40 the fuel and preventing choking in the fuel delivery passage through which fuel is forced into the retort by the plunger.

15. In combination in a stoker, a retort extending along the front wall of the stoker, 45 plungers for forcing fuel into the retort below the surface of the fuel contained therein, grate bars located in parallel relation and extending from the retort rearwardly, a fuel agitating member on which the ends of the 50 grate bars are mounted, a dump grate located adjacent to said member, and means for actuating said plungers, said grate bars and said dump grate.

16. In combination in an underfeed stoker, 55 a retort extending along the front wall of the stoker, grate bars located in parallel relation and extending from the retort rearwardly, a movable air delivering member supporting the rear ends of the grate bars, 60 means for transmitting reciprocatory motion to certain of said grate bars, and means located within the retort and actuated by the moving grate bars for breaking up the fuel entering the retort.

17. In an underfeed stoker, a retort, mov-

able grate bars for receiving fuel from said retort, a movable fuel agitating and impelling member on which one end of each grate bar is mounted, a dump grate mechanism, located adjacent to said member and 70 means for actuating said grate bars, and for imparting motion through said grate bars to said member.

18. In a stoker, a plurality of grate bars located in parallel relation and each having 75 an air delivery passage formed therein, and an air box for delivering air to said passages having a movable fuel impelling wall upon which the ends of said grate bars are mounted and which is adapted to be oscillated by the said bars.

19. In a stoker, a plurality of moving grate bars, having an air delivery passage formed therein, an air box for delivering air under pressure to the passages of said 85 grate bars having a movable fuel impelling air delivering member forming a wall of said air box and supporting the end of at least one grate bar, and a dump grate located adjacent to said member and onto which 90 fuel is moved by the cooperation of said moving grate bars and said member.

20. In a stoker, a plurality of moving grate bars having an air delivery passage formed therein, an air box for delivering 95 air under pressure to the passages of said grate bars, a dump grate for receiving fuel discharged from said grate bars, the said air box having a movable member forming a wall of said air box and supporting an end 100 of at least one of said grate bars, for agitating the fuel on said dump grate.

21. In combination in a stoker, a pivotally mounted dump grate, actuating mechanisms therefor including a stop for holding said 105 grate in a closed position, and power actuated means for swinging the free end of the grate upwardly from normal closed position and then downwardly below normal position during the dumping operation.

22. In combination in a stoker, a pivotally mounted dump grate, an operating lever, a pivot for the lever, a link pivoted to the free end of the lever and operatively connected to the grate by a link pivot, means for oscillating the lever so that the free end passes through a line cutting the lever pivot and the link pivot, and stop means for limiting the movement of the lever so that it supports the grate in closed position when the free end of the lever is at one side of the 115 said line.

23. In combination in a stoker, a pivotally mounted dump grate, an operating lever, a pivot for the lever, a link pivoted to the free end of the lever and operatively connected to the grate by a link pivot, means for oscillating the lever so that the free end passes through a line cutting the lever pivot and the link pivot, and adjustable stop means 120

for limiting the movement of the lever so that it supports the grate in closed position when the free end of the lever is at one side of the said line.

- 5 24. In combination in a stoker, a pivoted dump grate, a power actuated rack, a gear meshing with the rack, and a link connecting the free swinging end of said grate and the gear in such a manner that the grate

is moved upward prior to a downward move- 10
ment effected by the actuating mechanism.

In testimony whereof, I have hereunto
subscribed my name this 29th day of August,
1917.

CHARLES F. MILLER.

Witness:

C. W. McGHEE.
